United States Patent Office

Des. 198,623
Patented July 14, 1964

198,623

CHAIR

Samuel D. Lockshin, Northampton, Mass., assignor to
Hampden Specialty Products Corporation, Easthampton,
Mass.

Filed Sept. 27, 1962, Ser. No. 71,888

Term of patent 14 years

(Cl. D15—1)

FIG. 1

Des. 198,623

PAGE 2

FIGURE B

FIGURE 1

The paneled back of the chair is substantially similar in appearance to the front thereof.

I claim:

The ornamental design for a chair, as shown and described.
